(57) **CLAIM**

The ornamental design for container accessories, as shown and described.

DESCRIPTION

FIG. 1 is a top, front, right perspective view of container accessories showing our new design;

FIG. 2 is a top, front, left perspective of a bag accessory of the container accessories showing our new design;

FIG. 3 is a bottom, rear, right perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The even-length broken lines within the shaded area represent stitching. The broken lines immediately adjacent to the shaded area define the bounds of the claimed design and form no part thereof. The broken lines depicting the remainder of the container accessories show features that form no part of the claimed design.
